IGNITION SYSTEM FOR INTERNAL-COMBUSTION ENGINES.

Application filed July 10, 1919. Serial No. 309,943.

To all whom it may concern:

Be it known that I, WILLIAM C. BRINTON, Jr., a citizen of the United States, residing at Kennett Square, county of Chester, and 5 State of Pennsylvania, have invented a new and useful Improvement in Ignition Systems for Internal-Combustion Engines, of which the following is a full, clear, and exact description, reference being had to the 10 accompanying drawings, which form a part of this specification.

The object of my invention is to provide new and improved means for continuously supplying an unvarying current to spark 15 plugs in the secondary circuit of ignition systems for internal combustion engines, regardless of atmospheric conditions.

It has been found that the efficiency of the secondary or high tension current in 20 ignition systems is materially impaired by the presence of what I have herein termed static electricity, which varies with the atmospheric conditions and acts at certain times to cause a sluggish discharge at the 25 spark plugs, resulting in a lagging spark.

Heretofore the presence of static electricity has been recognized and it has been observed that, in addition to causing the spark to lag, it breaks down the condenser, due to 30 the fact that although the static has a very low amperage, it has at times a very high voltage, greatly in excess of the capacity of the condensers ordinarily used in ignition work, and at the same time tends to pit the 35 points of the contact maker and interrupter due to arcing.

I have found that the static is greatest in the high tension line between the secondary coil and the distributor wherein the current 40 tends to back up between contacts, although it is also present to a lesser but serious degree in the spark plug leads.

Heretofore the spark plug leads have in some instance been carried loosely in a metal 45 tube suitably grounded for the purpose of preventing induction from one wire to another. The leads contact with the tube at intervals and no doubt a certain amount of the static is removed.

50 This induction-preventing provision, however, is inefficient to neutralize the static, because the greatest effect of the static is not felt in the spark plug leads, but behind the distributor, and because the leads are car-

ried loosely in the metal tubing and have 55 contact with it only at relatively widely separated intervals. In addition, it has been found that moisture gets into the tube from condensation, causing the leads to short circuit. 60

In accordance with my invention, I provide means for positively drawing off or draining the static between the secondary coil and the distributor and from the spark plug leads and rendering the system entirely 65 free from its influence.

Referring to the accompanying drawings in which I have illustrated my invention,—

Fig. 1 is a diagrammatic view of an ignition system involving my invention. 70

Fig. 2 is a view, partly in section, of a spark plug lead assembly involving a detail of my invention.

Fig. 3 is a cross-section along line 3—3 of Fig. 2. 75

Fig. 4 is a view, partly in section, of a spark plug lead assembly involving a modification of my invention.

Fig. 5 is a cross section along line 5—5 of Fig. 4. 80

Fig. 6 is a cross-section along line 6—6 of Fig. 1.

A battery *a*, suitably grounded at *b*, is connected to the primary coil *c*, which in turn is connected with a movable contact *d* 85 adapted to be intermittently moved into and out of contact with a contact *e* by the cam *f* and spring *x*. Contact *e* is grounded at *g*, and a condenser *h* is connected between contacts *d* and *e*. 90

A secondary coil *i*, surrounding the primary coil *c*, is grounded at *j* and connected to a distributor *k* by means of the cable *l*. The leads *m* connect the distributor with spark plugs *n* on cylinders *o*. 95

The leads *m* are positioned about and firmly bound to a metal rod *p*, the ends of which are bent to form feet and suitably fastened to a convenient part of the engine or other fixed part, to support and ground 100 the bar. The leads are covered with a suitable covering *r* to protect them from moisture, oil, dust, etc.

The leads *m* may be run through a metal tube *s*, shown in Figs. 4 and 5, in which 105 they are adapted to fit tightly, so as to insure their continuous contact with the tube throughout their length, the tube being fas-

25

tened to and grounded on the engine. If desired, some material which will harden may be run into the tube *s* to fill the interstices between the leads, keep them firmly contact- ed with the tube and exclude moisture. The metal plate *u*, which conforms to and fits tightly against the insulation *t* of cable *l*, is held in tight contact with the cable by means of any suitable covering or wrapping *v* and is grounded at *w*. The plate *u* may, of course, be replaced by a metal tube or wire coil adapted to entirely surround the cable *l*.

In operation, the static electricity present in the high tension cable *l* passes through the insulation *t* because of its high voltage and into the plate *u*, from which it is drained into the ground *w*, thus rendering it entirely innocuous and preventing the harmful results caused by it, as heretofore pointed out.

Any static electricity present in the spark plug leads is, likewise, drained to the ground from the rod *p*, or tubes *s*, into which it passes from the leads, due to their constant contact with the bar throughout its length.

Having now fully described my invention, what I claim and desire to protect by Letters Patent is:

An ignition system for internal combustion engines, comprising a primary circuit including a primary coil and an interrupter, a secondary circuit including a secondary coil in inductive relation to the primary coil, a distributor, an insulated wire leading from the secondary coil to the distributor, a spark plug for each cylinder of the engine, an insulated wire for each spark plug leading from the distributor, a grounded static current drain in operative relation with the wire leading from the secondary coil to the distributor; and a second grounded static current drain in operative relation with all the wires leading from the distributor to the spark plugs, whereby the static electricity in the wires on both sides of the distributor are grounded.

In testimony of which invention, I have hereunto set my hand, at Philada., Penna., on this 27th day of June, 1919.

WILLIAM C. BRINTON, JR.
